UNITED STATES PATENT OFFICE

CHARLES MEYER; OF NEW YORK, N. Y.

IMPROVEMENT IN CANS FOR PAINT, &c.

Specification forming part of Letters Patent No. 150,342, dated April 28, 1874; application filed April 3, 1874.

To all whom it may concern:

Be it known that I, CHARLES MEYER, of the city, county, and State of New York, have invented a new and useful Improvement in Cans and Jars; and I do hereby declare the following to be a full, clear, and exact description thereof, which will enable those skilled in the art to make and use the same, reference being had to the accompanying drawing forming part of this specification, in which drawing—

Figure 1 is a vertical section of my improvement. Fig. 2 is an inverted plan view of the cover. Fig. 3 is a plan view of the top of the can or jar made according to my invention, the cover and packing-ring being removed.

Similar letters indicate corresponding parts.

This invention relates to cans and jars of metal, glass, or other material; and consists in an improved method of fastening the covers thereto. The top of the can or jar is provided with an internal locking-flange, which is recessed at one or more points to receive the locking-arms of the cover, and permit them to be brought under the divisions of the locking-flange, the arms of the cover, as well as the flange of the can or jar, being bent and constructed in such a manner with reference to each other that the arms can be brought beneath the flange, and they be made to engage each other with a screw-like action. The top of the can or jar is provided with a seat near its outer edge to receive a packing-ring or gasket, and I prefer to make such seat of a ridge shape to fit a corresponding groove in the cover. The cover consists of a disk of a diameter equal to or a little greater than that of the top of the can or jar, and it is provided with lugs or thumb-pieces, which enable me to tighten or loosen the cover with the hand. Upon the under side of the cover are arranged locking-arms, which enter the recesses in the locking-flange of the vessel, and which, by being turned under the locking-flange, draw the cover close to the can or jar, and produce a tight joint between them.

The letter A designates a tin can, which is open at top, except that it has an inner horizontal flange, B, which forms, with the can, a locking device to fasten the cover and can to each other. The flange B consists of a plate

whose outer edge is turned over and soldered to the edge of the can; but the plate, before it is applied to the can, is cut out by a die-cutter to the shape shown in the drawing, or to whatever shape is required to conform to and admit the locking-arms of the cover, and it is, when being cut, pressed by the die in such a manner as to turn over its outer edge C, and produce a ridge, D, on its top-surface, to form a seat for the cover, and for the packing-ring O. In the example here shown, the flange B is made with six projections, E; separated from each other by recesses F, to correspond to the locking-arms of the cover; but it is evident that a less number can be used with good effect, and therefore I do not confine myself to any particular number of recesses or projections for the flange, or to any particular number of locking-arms for the cover, so long as the cover and can are locked to each other by the method described. The projections E of the locking-flange are bent into an inclined position, so that each forms a segment of a screw-thread, and their under side is provided with a ridge, G, which increases in thickness in the direction toward which the locking-arms of the cover are to be turned, so that the arms are tightened as they are turned against the ridges. The inclined positions of the projecting parts E of the locking-flange, and the ridges G thereon, can be produced by the action of the dies when the flange is being cut, but, if desired, the ridges can be produced by solder or other methods. The cover H consists, in this example, of a flat metallic plate, provided with four lugs, I, projecting, at equal distances apart, from its edge, so as to form thumb-pieces for turning the cover upon the can by hand. The lugs I may be less in number, or, instead of them, lugs or depressions may be formed on the top of the cover to receive a wrench for turning the cover. From the under side of the cover project locking-arms J, which are bent to correspond to the inclined positions on the locking-flange of the can. In this example, these arms are formed on the edge of a plate, K, which is riveted to the under side of the cover. The under side of the cover, near its edge, is provided with a groove, L, arranged so as to receive the ridge-seat D of the can, and help make a tight joint.

The ridge D and the groove in the cover serve also as a guide to the cover in adjusting it on the can.

My invention is applicable to glass jars, as well as to metallic cans, and the vessels to which my invention is applied can be used for holding paints, as well as fruit and other articles, which it may be desired to keep air-tight.

What I claim as new, and desire to secure by Letters Patent, is—

1. A can or jar provided with surrounding ridge-seat D and a horizontal flange, B, having projections E, extending inwardly over a portion of the mouth of the can or jar, in combination with a cover, the locking-arms J of which pass under the projections E, substantially as described, for the purpose specified.

2. The horizontal flange B, having projections E, provided with inclined ridges G, in combination with the cover H, having the bent locking-arms J, substantially as described.

3. The combination of the flange B, having the projections E, ridge-seat D, and inclined ridges G with the cover H and its locking-arms J, substantially as described.

This specification signed by me this 31st day of March, 1874.

CHARLES MEYER.
